UNITED STATES PATENT OFFICE.

LOUIS A. MILLER, OF KANSAS CITY, MISSOURI.

GAME DEVICE.

Application filed August 9, 1926. Serial No. 128,254.

This invention relates to games and amusement devices, particularly those of the projectile type, and has for its object the provision of a novel and interesting game embodying the employment of a projectile in combination with either a playing court or a playing board or target, depending upon whether the game is to be played outdoors or indoors.

10 An important object is the provision of a game involving the use of an aerial projectile which may be thrown, kicked or otherwise propelled and which is adapted to penetratively engage within the surface of 15 the ground in a playing court or within the surface of a playing board or target, the projectile being of such specific formation as to be capable of penetrating the surface in several different positions, the position 20 governing the amount scored at each play.

Another object is the provision of a game device in which the court or playing surface is marked off in a peculiar manner and provided within certain areas with numerical indicia adapted to cooperate or be used 25 in conjunction with the points gained by sticking of the projectile in the playing surface at these areas for determining the score resulting from the individual play.

30 Another object is the provision of a game device of this character in which the playing court or surface may be arranged in different manners depending upon the space available and other circumstances.

35 An additional object is to provide a game of this type in which the projectile itself will be simple and inexpensive to manufacture, easy to operate, certain in action, durable in service, and a general improvement 40 in the art.

With the above and other objects and advantages in view, the invention preferably consists in the combination of a playing surface or court and projectile to be hereinafter more fully described and claimed, 45 and illustrated in the accompanying drawings in which:

Figure 1 is a view of a court used in playing the game, the initial position of the projectile being shown thereon,

50 Figure 2 is a view of a playing surface which might be that of a court but which

is particularly designed for use as a target against which the projectile may be thrown,

Figure 3 is a perspective view of the projectile alone,

Figure 4 is an elevation thereof showing one scoring position,

Figure 5 is an elevation showing another scoring position,

Figure 6 is a similar view showing still another scoring position, and

Figure 7 is an elevation showing an additional scoring position.

Referring more particularly to the drawings, and especially Figures 3 to 7 inclusive, I have shown the projectile used in the playing of the game, this projectile being designated as a whole by the numeral 10 and being of substantially T-shape or resembling a jack-knife with two blades open, one extending in alinement with the handle and the other extending at right angles thereto. The size of this projectile would necessarily depend upon whether the game is to be arranged for outdoor or indoor playing, it being quite obvious that in the first instance the projectile would be considerably larger than in the other case.

This projectile 10 is preferably formed 80 from a single piece of metal and includes a handle portion 11, coextensive with which is a portion 12 which may be considered a blade and from which extends a lateral blade 13. Both blades 12 and 13 are pointed as at 14 so that either will be capable of sticking into the ground or the surface of a playing board, target or the like. The handle 11 is so shaped and of such size with respect to the blades as to insure proper balancing so that the projectile will fly true 85 when propelled in any manner, whether by hand, foot or by means of some implement.

Regardless of the playing surface in connection with which the projectile is used, it 90 will be clear that there are various positions which may be assumed when it comes to rest in penetrating engagement with the surface. In Figure 4 I have shown the blade 13 as in penetrating position with the handle 11 tilted downwardly, whereas Figure 5 shows the same blade in penetrating position with the handle 11 and blade 12 extending horizontally. Another possible position

is illustrated in Figure 6 which shows the device inclined with the blade 12 in penetrating position. It is also evident that the device may extend vertically with the blade 12 penetrating the ground or other surface, as disclosed in Figure 7. It is intended that each of these positions should have a different significance in scoring, as for instance the positions shown in Figures 4, 5, 6 and 7 may indicate one, two, three and four points respectively. Of course the number of points and their relation to these positions is arbitrary as any other arrangement and relation may be adopted, these being mentioned simply by way of illustration.

As mentioned above the projectile is capable of employment in connection with a court 15 such as that illustrated in Figure 1, it being intended that this court be laid out on the ground and defined by longitudinal lines 16 and transverse lines 17 which may be the same or unequal distances apart as preferred, these lines defining a plurality of areas 18 which are preferably consecutively numbered.

In the playing of the game in connection with a court of this type, it is intended that the projectile be initially driven into the soil, if the court be outdoors, or into whatever material bears the playing surface or court, if it be constructed for indoor use, at a point near but outwardly of one end-most transverse line, as shown in Figure 1. It is a simple matter to place the projectile in such position as the operator may readily grasp it by the handle 11 and by swinging the device into forcible engagement with the ground or other surface cause the blade to engage penetratingly therein. The projectile having been thus positioned, it is given a quick or sudden jerk by means of the hand, foot or a propelling stick or other device so as to cause the projectile to fly up into the air and turn or spin while passing therethrough. The force of the jerk or blow is gauged to insure the projectile dropping onto the court or playing surface and it is preferable that it be caused to travel the maximum distance while still remaining within the confines of the court or playing surface inasmuch as the areas 18 have a progressively increasing score value as they recede from the starting point or place where the projectile is initially stuck. If the projectile lands flat nothing is scored but if it penetrates the ground in any one of the four positions illustrated in Figures 4 to 7, the player receives a certain number of points depending upon the specific position, as above explained. The intention is that the number of points thus obtained be multiplied by the number appearing in that area 18 in which the projectile lands. Any desired number of players may engage in the game and any preferred or suitable rules may

be formulated as may be found necessary in actual development and there may be certain penalties and advantages incident to various contingencies which may arise, all of which would be well calculated to increase the interest in and entertainment to be derived from the playing of the game.

While Figure 1 discloses a court primarily intended for outdoor use, Figure 2 discloses a modified form which, though capable of being inscribed or laid out upon a ground surface is better adapted for use if the game be constructed to be played indoors. This type of playing surface disclosed in Figure 2 lends itself readily to the formation of a target which may be leaned against an embankment, tree or other support if used outdoors, or which might be suspended upon the wall or laid flat upon the floor, a table or the like if used indoors. If the game be constructed on a small scale for indoor use it is evident that the projectile would probably be used in a manner analogous to the handling of a knife in the playing of a popular game known as "mumbley-peg". The type of playing surface disclosed in Figure 2 consists of a plurality of concentric circular lines 19 which define concentric ring-like areas 20 consecutively numbered as shown or in any other arbitrary manner. If this type of playing surface is employed scoring would be effected in a manner similar to that above described in connection with the court 15, the same rules as to the number of points gained by the sticking in of the projectile in different positions applying, these points being intended to be multiplied by the number appearing in the ring-like area in which the projectile may stick.

From the foregoing description and a study of the drawings it will be apparent that I have thus provided a simple and easily played game and inexpensive apparatus for carrying it out, the combination being such that a high degree of entertainment may be obtained with the exercise of a reasonable degree of skill and care. Naturally, the element of chance enters into the game to a certain extent but skill is the principal factor especially in gauging the distance to the areas which count the highest in scoring.

While I have shown and described the preferred embodiments of the invention, it should be understood that I reserve the right to make such changes in the details of formation of the projectile as well as the court or playing surface, as will not depart from the spirit of the invention or the scope of the subjoined claim.

Having thus described the invention, I claim:

A game of the character described comprising the combination of a playing surface embodying a plurality of areas differently

numbered, and an aerial projectile adapted to impinge upon and penetrately engage the surface, the projectile having a plurality of penetrating points engagement of which within the playing surface is determined by chance, the various possible penetrating positions of the projectile giving different

score points and said score points cooperating with the numbering of an area in which the projectile lands to give a total score for an individual play.

In testimony whereof I affix my signature.

LOUIS A. MILLER.
